ATTORNEYS

UNITED STATES PATENT OFFICE.

FRANK P. STEIL, OF CUDAHY, WISCONSIN.

SHOE.

Application filed November 15, 1923. Serial No. 674,852.

To all whom it may concern:

Be it known that I, FRANK P. STEIL, a citizen of the United States of America, and resident of Cudahy, in the county of Milwaukee and State of Wisconsin, have invented new and useful Improvements in Shoes, of which the following is a description, reference being had to the accompanying drawings, which are a part of this specification.

10 The invention relates to stitch-down shoes.

As usually constructed, shoes are provided with a lining, generally of fabric, under the vamp. This lining, particularly in the 15 region of the ball of the foot or the widest part of the shoe, is subjected to heavy stretching strains because of the natural tendency of the foot to spread or stretch the shoe in this locality, and the result is the 20 vamp itself is stretched and the shoe loses its shape and neat appearance and the foot itself may spread or run over the side of the shoe. The object of this invention is to provide a reinforcement for the lining 25 extending transversely of the shoe beneath the vamp in the region of the ball or widest part of the foot, so as to prevent stretching and distortion of the vamp.

This invention further consists in the 30 several features hereinafter set forth and more particularly defined by claims at the conclusion hereof.

In the drawings: Fig. 1 is a plan view of the 35 shoe embodying the invention, part of the vamp being broken away; Fig. 2 is a section taken on the line 2—2 of Fig. 1.

As shown, the shoe 3 has a vamp 4, a fabric lining 5, an inner sole 6 beneath which the edges 7 of the lining extend and 40 to which they are secured in any suitable way, as by adhesive, a mid-sole 8 and an outer sole 9. As is usual with stitch-down shoes, the extended edge 10 of the vamp is secured to the sole 8 by staples 11, or other suitable means, and the welt 12, the edge 10, sole 8 and outsole 9 are secured together by stitching 13.

The construction of shoes thus far described is well known and it has been found 50 that with such a construction, because of the

constant tendency of the foot to spread in its widest part, that is, in the region of the ball of the foot, the lining stretches and consequently the vamp stretches in this region and becomes loose and gets out of shape, thus destroying the appearance of the shoe and tending to produce overrunning. To avoid these difficulties, I have provided a reinforcement consisting of a 55 relatively wide strip 14 of strong, tightly woven fabric, hence relatively inelastic, extending over and secured to the lining or vamp in the region of the ball of the foot or the widest part of the shoe, by suitable adhesive, and preferably extending beneath 60 the inner sole 6 to which it is secured in any suitable manner and with its ends 15 overlapped and secured together, in any suitable manner, to form a band. This band effectively prevents the lining from stretching 65 and hence allows the vamp to retain its initial form.

I desire it to be understood that this invention is not to be limited to any particular construction or arrangement of parts except in so far as such limitations are included in the claims.

What I claim as my invention is:

1. In a stitch-down shoe, the combination, with the vamp, a fabric vamp-lining, and so the inner sole, of a relatively inelastic fabric strip beneath the vamp and extending over and across the lining at the widest part of the shoe and extending beneath and secured to the inner sole to prevent stretching 85 of the lining and distortion of the vamp.

2. In a stitch-down shoe, the combination, with the vamp, a fabric vamp-lining and the inner sole, of a relatively inelastic fabric strip beneath the vamp and extending over 90 and across the lining at the widest part of the shoe and beneath the inner sole with its ends overlapped beneath said inner sole and secured thereto and together, said strip forming a reinforcing band to prevent 95 stretching of the lining and distortion of the vamp.

In testimony whereof, I affix my signature.

FRANK P. STEIL.
